GOLF BALL CLEANER

Clarence Sundahl, Kansas City, Mo.

Application February 27, 1933, Serial No. 658,774

3 Claims. (Cl. 15—21)

This invention relates to golf ball cleaners of that class in which one or a plurality of balls are caused to travel circularly and through a cleaning solution and in frictional contact with a relatively stiff brush or brushes, and my object is to produce an efficient cleaner of simple, strong, durable and inexpensive construction.

With this general object and others as will hereinafter appear in view, the invention consists in certain novel and peculiar features of construction and organization of parts as hereinafter described; and in order that it may be fully understood, reference is to be had to the accompanying drawing, in which:—

Figure 1 is a broken front elevation of a cleaner embodying the invention.

Figure 2 is a rear elevation of the same with the supporting element broken and a clamping element omitted.

Figure 3 is a central vertical section of the cleaner.

Figure 4 is a section on the line IV—IV of Figure 3.

Figure 5 is a section on the line V—V of Figure 3.

Referring to the drawing in detail, it will be seen that there is a sheet metal casing of circular form comprising a lower or body portion 1 and an upper or cover portion 2, hinged at 3 to the back wall of the body portion. Fitting within the casing against the circumferential wall thereof are arcuate shaped brushes 4 with the bristles facing inwardly, screws 5 or the like securing the brushes in place. The brush in the body portion is preferably of sectional type for convenience of installation and replacement when necessary.

Arranged centrally within the housing is a rotor comprising a pair of disks 6 connected by arched cross bars 7 spaced uniformly apart a distance greater than the diameter of a golf ball. The disks are spaced apart a distance less than the diameter of a golf ball and are of such diameter that a ball in contact with their peripheries shall be partly embedded in the opposite brush so that as the rotor is turned, a cross bar shall cause a ball ahead of it to follow a circular course.

At diametrically opposite points each disk between the cross bars, is flared out at its periphery as at 6a, the flared portions of one disk being disposed at right angles to those of the other disk. This arrangement is provided so that the balls B, shall be caused to move laterally in each revolution of the rotor, in order that their entire circumferential area shall be acted on by the brushes in each revolution, and not leave un-

cleaned or partly uncleared spots at opposite sides as sometimes happened when the device was tested with two perfect circular disks 6 of the same diameter. It is possible to use two disks of unequal diameter for effecting lateral movement of the balls as they are circulated by the rotor (as hereinafter explained), but it is preferred to flare both disks as described and shown as giving more frequent lateral movements to the balls than by the use of complete or unmodified disks of unequal diameter. By providing for lateral shaft of the balls, they are also caused to more certainly turn around their own axes under the resistance offered by the brushes so that the cleaning action shall be more efficient and expeditious.

The rotor is mounted non-rotatably on a shaft 8 journaled in the front and back walls of the casing, and is provided at its front end with a crank handle 9. At the rear end, the shaft has a circular groove 10, said end fitting in a closed socket 11 secured to the casing, and to prevent dislocation of the shaft, a set screw 12 is mounted in the socket and engages the groove 10. A rectangular hood 13 secured to the back wall of the casing, projects therefrom a slightly greater distance than socket 11 and overhangs the latter, and vertically below said socket, near the bottom of the casing, is a rigid stud bolt 14.

As a support for the casing there is provided a standard 15 of channel form. For use at different points of a golf course, the standards will preferably be erected in concrete bases, not shown. For use within a locker room or the like, the standard will preferably be secured to a suitable wood or metal base, not shown, for convenience of portability.

To insure firmness of support of the casing by the standard, the latter is proportioned to fit snugly at its upper end within the hood 13 and around the socket 10, and to clamp the casing and standard firmly together, the latter has a slot 17 through which bolt 14 projects for engagement by a clamping nut 18. The upper end of the slot 17 is a shorter distance from the bolt 14, than the depth of the hood, so that merely unclamping operation of the nut will not permit removal of the casing from the standard, as to remove the casing it must be first swung to an angular position, as indicated by dotted lines, Figure 3, and to permit it to be so disposed, it is not only necessary to remove the nut from bolt 14, but the upper end of the standard must be tapered as indicated at 16. This taper permits the casing, when the nut is removed, to be swung forwardly

at the bottom until the bolt 14 is entirely withdrawn from slot 17. The casing can then be lifted off the standard.

As removal of the nut might be followed by misplacement thereof, it is swivelled in a large washer or ring 19, chained as at 20 to the standard and as it is not desirable to give unauthorized persons an opportunity to remove the casing, the rear extremity of the stud bolt has an opening 21 for engagement by the shackle member of a padlock 22, which shackle provides for convenient support of one or more perforated or grommeted towels 23 for drying a ball after it is cleaned. When the casing is removed, the padlock, carrying the towel, can be fastened on the chain and thus guard against misplacement and annoyance or delay incident thereto.

In operation, the cover is raised and reclosed after a ball is dropped in the cleaner onto the rotor. The crank handle is then operated and the cross-bar immediately back of the ball, forces the same to travel circularly against the brush, the latter offering the necessary resistance to insure such travel and to brush mud from the ball. The bristles, while stiff enough to function as explained, will yield sufficiently to embed a large area of the ball and will offer enough resistance to cause it to turn on its own axis so that the cleaning action of the brush shall affect the entire circumferential area of the ball. In practice, a few turns of the handle generally serve to clean the ball thoroughly.

Any suitable cleaning solution (not shown), may be employed, such as water and soap powder. When the solution gets muddy, the casing can be removed by a caddy or player, if equipped with a key for the padlock, and the muddy solution poured out. If this is not sufficiently effective, the set screw 12 can be withdrawn, so that the shaft, rotor and brushes can be quickly removed, the brush in the body portion preferably consisting of three sections for convenience of installation and removal. The two side sections will be secured by screws 5, the bottom section being held firmly by the side sections. The parts can be quickly reassembled and a fresh cleaning solution supplied.

It will be apparent that the cleaner illustrated can be used without danger of soiling clothing or the hands, that the operating parts can be stored in winter, and that the servicing of the cleaners can be effected more expeditiously and economically than cleaners permanently located, to which cleaning appurtenances must always be car-

ried. It will be understood that while I have illustrated and described the preferred construction, the cleaner is susceptible of various changes in detail within the spirit and scope of the appended claims.

I claim:—

1. In a golf ball cleaner, a casing, an arcuate brush within the casing disposed with its bristles facing inwardly, a rotor within the casing and of smaller diameter than the brush, the axis of the rotor substantially coinciding with that of the inner face of the bristles, the rotor comprising a pair of disks spaced apart less than the diameter of a golf ball and cross-bars connecting the disks to apply pressure on golf balls resting on the disks to cause the balls to travel along and in frictional contact with the brush, one disk having a portion of its edge bent outwardly and away from the other disk at a point which is opposite an unbent part of said other disk.

2. In a golf ball cleaner, a pair of spaced substantially parallel disks connected together by spaced cross bars projecting outward beyond the peripheries of the disks, a portion of the edge of one disk being bent out and away from the other disk at a point which is opposite a part of said other disk which is not bent.

3. A golf ball washer comprising a circular casing having flat sides and composed of a stationary major portion and a minor cover portion hinged at one of its flat sides to a flat side of the major portion, a circular brush secured within and paralleling the perimeter portion of the casing, the brush being sectional and the section within the cover being movable with the latter to give access to the brush section within the major portion of the casing, the bristles of the brush facing toward the axis of the casing, a shaft journaled in the casing axially thereof, a crank handle for the shaft at the outer side of the casing to effect rotation of the shaft, and a ball carrier mounted on the shaft to rotate therewith and spaced from and disposed within and concentrically of the brush, and consisting of a pair of disks spaced apart a distance less than the diameter of a golf ball and provided with a plurality of arms rigid with and projecting outwardly from and over the space between the disks, the arms being spaced apart to accommodate golf balls for disposal on and supported by the peripheral edges of the disks and to be held by the disks in frictional engagement with the brush.

CLARENCE SUNDALH.
